US0D1102285S

(12) **United States Design Patent** (10) **Patent No.:** **US D1,102,285 S**
(45) **Date of Patent:** **** Nov. 18, 2025**

(54) **THERMOSTAT**

(71) Applicant: **Shenzhen Meihang Electronic Technology Co., Ltd.**, Shenzhen (CN)

(72) Inventor: **Guangming Liao**, Neijiang (CN)

(73) Assignee: **Shenzhen Meihang Electronic Technology Co., Ltd.**, Shenzhen (CN)

(**) Term: **15 Years**

(21) Appl. No.: **29/947,862**

(22) Filed: **Jun. 18, 2024**

(51) LOC (15) Cl. **10-05**

(52) U.S. Cl.

USPC **D10/50**

(57) **CLAIM**

The ornamental design for a thermostat, as shown and described.

DESCRIPTION

FIG. 1 is a front, right and top perspective view of a thermostat, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the thermostat that form no part of the claimed design.

1 Claim, 8 Drawing Sheets
